UNITED STATES PATENT OFFICE

122,338

DESIGN FOR A BOTTLE

Clarence F. Miles, Worcester, Mass.

Application April 13, 1940, Serial No. 91,650

Term of patent 14 years

To all whom it may concern:

Be it known that I, Clarence F. Miles, a citizen of the United States, residing at Worcester, in the county of Worcester and State of Massachusetts, have invented a new, original, and ornamental Design for a Bottle, of which the following is a specification, reference being had to the accompanying drawing forming part thereof.

Fig. 1 is a side elevational view of a bottle showing my new design;

Fig. 2 is a rear elevation thereof;

Fig. 3 is a front elevation thereof; and

Fig. 4 is a bottom plan view.

I claim:

The ornamental design for a bottle, as shown.

CLARENCE F. MILES.
